UNITED STATES PATENT OFFICE.

WILLIAM B. ST. CYR AND FRANK R. McDONALD, OF MINNEAPOLIS,
MINNESOTA.

SAFETY-SWITCH.

SPECIFICATION forming part of Letters Patent No. 381,034, dated April 10, 1888.

Application filed October 4, 1887. Serial No. 251,388. (No model.)

To all whom it may concern:

Be it known that we, WILLIAM B. ST. CYR and FRANK R. McDONALD, citizens of the United States, residents of the city of Minneapolis, county of Hennepin, State of Minnesota, have invented a certain new and useful Safety-Switch, of which the following is a specification, reference being had to the accompanying drawings.

Our invention relates to railways. Its object is to save human life.

Destructive railway disasters are due more frequently to an open switch than any other one cause. So far, as life is imperiled in this way, we remove the cause entirely by providing a device which will invariably close an open switch in advance of a train by motion communicated from the train itself.

Our invention consists of the construction hereinafter fully described, and particularly pointed out in the claims.

In the drawings, like figures referring to like parts throughout, Figure 1 is a plan view showing a portion of a main track and switch with our invention in working position, the shield or cap over the tripping-lever being removed. Figs. 2 and 3 are partial vertical cross-sections on the line X X' of Fig. 1, the former showing the rail-shifting mechanism as it appears when the switch is open and the latter as it appears when the switch is closed. Figs. 4 and 5 are views in side elevation and plan, respectively, of the safety rail-shifting lever detached. Figs. 6 and 7 are views in side elevation and plan, respectively, of the connecting-rod for shifting the rails by the common crank-lever switch. Figs. 8 and 9 are similar views of the safety tripping-lever. Fig. 10 is a side elevation showing the support for this lever; and Fig. 11 is a side elevation of a part of a locomotive-truck, showing the drop-pin for operating the safety tripping-lever.

A A represent the ties and B B' the switch head-blocks of a railway-track.

C C are the movable and C' C' are the fixed rails of the main track.

D D are the rails of a side track or switch. E E are chairs secured to the head-block B', supporting the ends of the three sets of rails in the customary manner.

F is a strong metallic bar, which is rigidly secured at its opposite ends to the under sides of the movable rails C C between the head-blocks B B'. It is provided with a hole in its center, of proper size to pass a strong bolt or pivot-pin.

G is a combined rail-shifting lever and pivoted locking device, enlarged or thickened up at its central point above and below into the boss g and provided with the central hole, j. This lever G has three arms, g', g'', and g'''. Of these the arms g' and g'' are of equal length, and the arm g''' is of about half the length of either of the other two and is set at right angles to the same in the horizontal plane. Each of the arms is provided with a hole or holes at its extremity for the attachment of connecting-rods, and the arm g' is provided with a hooked extremity, J, adapted to engage with a lug on the draw-bar of the common switch and detachably lock the two together, as hereinafter described.

H is a shield or guard-plate, having its ends bent at right angles to its length and secured in any suitable manner to the upper surface of base-bar F, and is also provided with a bolt-hole at its central point.

K is a headed bolt or pivot-pin, which passes through the coincident central holes in the base-bar, the shifting lever, and the guard, and is secured therein by a nut, or in any suitable way. It serves as a fulcrum for the shifting-lever G.

L L' are trip-lever supports, which are fixed lengthwise of the main track at some considerable distance, preferably about sixteen feet, on the opposite sides of the lever G and to the right and left of the center of the track. Each of these supports is composed of a base-piece, l, having its ends bent at right angles to its length and secured to the two adjacent ties, and a cap plate or shield, l', which is secured to the base-piece in such a manner as to leave a clear space between the two. These supports are preferably placed not exactly parallel to the rails, but at a slight angle to the same. The two parts l and l' are provided with coincident holes for a fulcrum-pin. Between these plates, by fulcrum-pin M, is secured the tripping-lever N, with its shorter arm, n, toward the outside and its longer arm,

n', toward the inside of the track. The longer arm, *n'*, is bent upon itself, so as to raise its outer extremity to a higher level than the pivotal point of the lever, and it is provided with a cam-surface, *n''*, inclining in the direction of the moving train. Connecting-rods *P P'* pivotally connect the outer ends of the lever-arms *g'* and *g''* with the outer arms, *n*, of the triple-levers *N N'*, respectively. A coiled retraction-spring, *Q*, is attached at one end to the extremity of the lever-arm *g''* and at the other to a staple or eyebolt, *q*, fixed in the adjacent movable rail *C*.

To the inside of the head-block *B'*, below the level of the rails and just outside the adjacent rail on the main track, is fixed an angle-iron, *R*, provided with a hole adapted to pass a connecting-rod, *S*. This connecting-rod *S* is pivotally attached by pivot-pin *s* to the lever-arm *g''* at its inner end, passes under the rails through the hole in the angle-iron *R*, and is provided with a right-angled extension or hook-shaped end, *s'*, and is of just sufficient length to a little more than reach from the lever-arm *g''* to the angle-iron *R*, when the switch is open, as shown in Fig. 1.

T is a switch-stand provided with a vertical crank-shaft, *T'*, of the ordinary kind.

W is a switch draw-bar or connecting-rod mounted at one end on the crank-shaft *T'* in the customary manner, and having at its other end a vertical extension or lug, *w*. This lug is provided with a transverse hole for a cross-pin, *w'*.

*The base-bar F is provided with a longitudinal slot, *f*, in the part lying directly under the hook *J* on the lever *G*. The draw-bar *W* is attached to the base-bar *F* by the lug *w* working through the slot *f*, and secured therein by the cross-pin *w'*.*

On the base-plate *F*, intermediate the inner end of the slot *f* and its center to a lug, *f'*, is pivoted at one end a gravity-actuated locking-lever, *Y*, which is of a length just sufficient to reach to and fall behind the pin *w'* when the shifting-lever has been tripped, as shown in Fig. 3. When in its normal position, its free end rests on the top of the pin *w'*.

Referring to Fig. 11, *Z* is part of a locomotive-truck. In suitable bearings on this truck, as *a a'*, is placed a vertically-movable tripping-bolt, *Z'*, which, by a system of levers, as *b b'*, is under the control of the engineer. This tripping-bolt, when in its lowermost position, is high enough to clear all tracks which it will have to cross with a sufficient margin, and is low enough to strike the tripping-lever *N* or *N'*, as shown in Fig. 1.

It is placed in the proper relative position on the locomotive-truck, so that it will strike the cam-surface *n''* on the lever-arm *n'* and clear the same after it has moved the lever *N* from the position shown in full lines to the position shown in dotted lines in Fig. 1.

It will be readily understood that instead of the bearings shown any suitable guide on the truck may be used for the purpose, and any

suitable system of levers extending to the engineer's cab may be adopted for the control of the rod. All that is necessary is that the 70 guide should be true and protected, and that the rod be moved positively within definite limits.

The operation of our invention is as follows: Suppose the switch to be open, then the normal position of all the parts will be as shown in full lines in Fig. 1. The common switch *T T'*, through draw-bar *W*, the lug *w*, and the hook *J* on the lever *G*, holds the movable rails *C C* to the side track, *D D*. As long as the hook *J* is 80 kept in engagement with the lug *w*, the rails *C C* cannot be shifted to the main track. Suppose a train to be coming along *C' C'* toward *C C*. The instant the tripping-rod *Z'* strikes the end of the tripping-lever *N'* the hook *J* is 85 withdrawn from behind the lug *w*, the base-bar *F* and the rails *C C* are free to move, the lug *w* sliding in the slot *f*, the angle-iron *R* becomes the point of resistance through the connecting-rod *S*, and the pivot-pin *s* becomes 90 the fulcrum, delivering the whole power through the system of levers on the base-bar *F* by the pivot-pin *K*, effecting instantaneous alignment of both parts of the main track. The initiation of this movement toward alignment after the lever has been tripped is made by the natural spring in the movable rails *C C*; but its completion is effected with absolute certainty and precision by the connecting-rod *S* and the system of levers, as described. The 100 flanges on the rail-chairs prevent the rails from going too far out, while the gravity-lock *Y*, falling behind the lug *w*, prevents the rails rebounding or springing backward toward the switch-rails after the tripping-rod *Z'* has passed 105 and released the tripping-lever *N* or *N'*.

The function of the spring *Q* is to retract the lever *G* to its normal position, set the triple-levers *N N'*, and hold the hook *J* in engagement with the lug *w*. In virtue of this spring, 110 the hook constantly hugs the lug and accidental displacement is thereby prevented. The proportions and positions of the co-operative parts are such that the hook *J* can only engage with one side of the lug *w*, and that only when 115 the said lug is thrown to its innermost limit within the slot *f*, as shown in Figs. 1 and 2. When the lug *w* is in any other position in said slot, the head of the hook bears against the face of the lug, as shown in Fig. 3.

It will be seen that in addition to its function as a shifting-lever, effecting the alignment of the two parts of the main track, the lever *G* also serves as a means of detachably connecting the movable rails with the draw-bar 125 of a common switch. Hence the movable rails are controllable by the common switch just as fully as if the safety-switch were not used. Considered as moving the rails, *G* is a rail-shifting lever; considered as locking the rails 130 to the draw-bar of the common switch, *G* is a pivoted locking device.

In addition to the function hereinbefore set out, the gravity-lock *Y* has the effect of indi-

cating the train which has left the switch open. Inasmuch as the movable rails cannot again be moved to the side track until the lock is raised, the first man seeking to use the side track will 5 learn that the safety-switch has been tripped. The inference will be that the last preceding train which used the side track must have left the switch open.

It has hereinbefore been stated that the trip-levers N and N' are placed about sixteen feet from the shifting-lever G . As to this, the only important points are two—viz., that both be far enough off to give an abundance of time for the closing of the switch in advance of the engine, and that the one on the part of the track having the movable rails be placed far enough away to be tripped and effect the shifting of the rails before the weight of the engine comes onto the movable or springing part of the rails. 15 This last point is absolutely essential; otherwise, the weight of the engine might, and probably would, prevent the shifting of the rails.

It should be noted that the trip-levers N and N' are located to the right and left of the center of the track, and that the tripping rod or bolt Z' is located to the right of the center of the locomotive-truck. Hence, whichever way the train may be coming the rod Z' will 20 strike only the first tripping-lever, passing clear of the other. It will be necessary to raise the tripping-rod whenever it is desired to back the engine over the switch or run in on a side track.

35 In order to make the safety-switch equally effective for engines moving backward as well as forward over the main line, all that is necessary is to provide two tripping-rods, one located to the right and the other to the left 40 of the center of the truck in corresponding relative positions. Care would then have to be taken to raise the one rod and lower the other, according to whether the engine was intended to move forward or backward.

45 The inner ends of the tripping-levers N N' are supported at a level sufficiently high to be struck by the rod Z' with positive certainty, and are yet low enough to afford an abundance of clearance under the lowest parts of any 50 engine or cars.

When the two parts of the main track are in alignment—or, in other words, when the switch is closed—the engine and train pass over the safety-switch without any disturbance 55 of the rails.

The tripping-levers and the shifting-lever are actuated, but without any effect on the rails.

The rod S , which may be called a "connecting-rod," "resistance-rod," or "movable fulcrum," we regard as a very material feature of our invention. It may vary from the form shown. All that is necessary is that it have a fixed point of resistance, as the angle-iron R , 60 beyond the point to which the pivot-pins, connecting it to the arm g' of the lever G , is to be drawn; that a limited lateral movement be al-

lowed either to the rod itself through the angle-iron or the lever-arm, or to its connections with the lever or fixed support, in order to allow the movable rails to be thrown to the side track, and that it be rendered rigid with its point of resistance, its pivot-pins becoming the fulcrum for the shifting-lever G before the tripping-rod Z' has passed the tripping-lever 75 N or N' .

It will be understood that minor changes may be made in our construction without departing from the spirit of our invention.

What we claim, and desire to secure by Letters Patent of the United States, is as follows:

1. In a railway switch, in combination, a suitable base-plate rigidly secured to the free ends of the movable rails and provided with a longitudinal slot, a switch draw-bar provided with a lug working in said slot, and a pivoted locking device secured to said base-plate and adapted to detachably engage said lug and rigidly connect said base-plate and draw-bar, as and for the purpose set forth. 80

2. In combination with the movable rails C C , the base-plate F , rigidly secured to said rails and provided with the slot f , a switch-stand, T , provided with a crank-shaft, T' , the draw-bar W , mounted at one end on said crank-shaft and provided at the other with the lug w , working in said slot, and with the cross-pin w' , securing the lug therein, and the pivoted locking device G J , secured to said base-plate, as and for the purpose set forth. 90

3. In a railway safety-switch, in combination with a common switch draw-bar, a base-plate rigidly connected to the free ends of the movable rails, a pivoted locking device secured to said base-plate and adapted to detachably engage with said draw-bar and lock it to said base-plate, a trip-lever mounted on a suitable support located at a suitable distance from the switch, a connecting-rod from said tripping-lever to said pivoted locking device, and a tripping-pin mounted in suitable bearings on the locomotive-truck and adapted to strike said tripping-lever and unlock said base-plate from said draw-bar, substantially as described, whereby the movable rails tend to align themselves with the fixed rails of the main track by their own elasticity. 105

4. In combination for closing an open railway-switch, a base-plate rigidly secured to the free ends of the movable rails, a bell-crank lever pivoted to said base-plate and having one arm lengthwise of the ties and the other lengthwise of the rails, a draw-rod or movable fulcrum pivotally secured at one end to the arm of said lever which is lengthwise of the 120 rails, and having its other end held, with allowance for a limited longitudinal movement, in a suitable fixed support near the rail-line, an actuating-lever mounted on a suitable fixed support located on the track at a suitable distance from the switch, a connecting-rod extending from said actuating-lever to the other or cross arm of said bell-crank lever, and an actuating-rod mounted on the locomotive. 125 130

truck and adapted to engage said actuating-lever, substantially as set forth, whereby the movable rails are aligned with the fixed rails of the main track positively by motion communicated from the moving train.

5 5. In a railway-switch, in combination, a base-plate rigidly secured to the free ends of the movable rails, a lever pivoted intermediate its extremities to said base-plate and having one arm lengthwise of the track, a draw-rod or movable fulcrum pivotally secured at one end to said lever-arm and having its other end held, with allowance for a limited longitudinal movement, in a suitable fixed support or base of resistance near the rail-line, substantially as described, whereby power applied to the free arm of said lever will close said switch.

20 6. In a railway safety-switch, in combination with a common switch draw-bar, a base-plate rigidly connected to the free ends of the movable rails, a pivoted locking device secured to said base-plate and adapted to detachably engage with said draw-bar and lock it to said base-plate, a tripping device adapted to trip said lock and disengage said base-plate and draw-bar by motion from a moving train, and a retraction-spring fixed at one end to a suitable base of resistance and directly or indirectly attached at one other to said pivoted locking device and adapted to restore said locking device to its normal position after it has been tripped, as and for the purpose set forth.

35 7. In a railway safety-switch, in combination with a common switch draw-bar, a base-plate rigidly connected to the free ends of the movable rails, a locking device secured to said base-plate and adapted to detachably engage with said draw-bar and lock it to said base-plate, and a tripping device adapted to trip said lock and disengage said draw-bar and base-plate by motion communicated from a moving train, substantially as and for the purpose set forth.

40 8. In a railway safety-switch, in combination with a common switch draw-bar, a base-plate secured to the movable rails, a combined locking device and rail-shifting lever pivoted to said base-plate, adapted to detachably lock together said draw-bar and base-plate and to shift the rails after the draw-bar and base-plate are unlocked, a tripping device provided with a rigid connection to said locking device and adapted to trip the same by motion from

the moving train, and a connection from said shifting-lever to a fixed point of resistance near the rail-line, substantially as described.

9. In a railway-switch, in combination, a suitable base-plate rigidly secured to the free ends of the movable rails and provided with a longitudinal slot, a common switch draw-bar provided with a lug working in said slot, a bell-crank lever having one arm lengthwise of the track pivoted to said base-plate and provided with a hook on the other arm adapted to detachably engage with said lug and lock together said draw-bar and base-plate, a trip-lever mounted on a suitable support at a suitable distance from the switch, a connecting-rod from said trip-lever to said bell-crank lever, a draw-rod or movable fulcrum connected at one end to a fixed base of resistance near the rail-line and at the other pivotally attached to the arm of said bell-crank lever lengthwise of the track, and a tripping-pin or actuating-rod mounted in suitable bearings on the locomotive-truck, substantially as and for the purpose set forth.

10. In a railway-switch, in combination, a suitable base-plate rigidly secured to the free ends of the movable rails and provided with a longitudinal slot, a switch draw-bar provided with a lug working in said slot, and a gravity-dog pivoted to said base-plate and adapted to fall behind said lug and lock the same in its outermost position, substantially as set forth.

11. In combination, the movable rails C C, the base-plate F, rigidly secured to said rails and provided with the slot f, the switch-stand 90 and crank-shaft T T', the draw-bar W, provided with the lug w, working in said slot, and the cross-pin w', securing it therein, the lever G g' g'' g''', provided with the hook J, pivoted to said base-plate, the draw-rod S, secured at 95 one end in the angle-iron R and at the other pivoted to the lever-arm g'', the trip-lever supports L L', the trip-levers N N', mounted on said supports, the connecting-rods P P', from the levers N N' to the arms g' g'', respectively, 100 the retraction-spring Q, attached at one end to the lever-arm g' and at the other to the staple q, fixed in rail C, and the drop-pin Z', mounted in bearings on the locomotive-truck Z, substantially as described.
